BY Fisher & Moore, ATTYS.

UNITED STATES PATENT OFFICE.

CHARLES F. ACKERMAN, OF CLEVELAND, OHIO.

FAUCET-SYRINGE.

964,730.

Specification of Letters Patent. Patented July 19, 1910.

Application filed January 27, 1909. Serial No. 474,430.

To all whom it may concern:

Be it known that I, CHARLES F. ACKERMAN, citizen of the United States, residing at Cleveland, in the county of Cuyahoga and State of Ohio, have invented certain new and useful Improvements in Faucet-Syringes, of which the following is a specification.

My invention relates to an improvement 10 in faucet syringes comprising a medicating device and other parts, substantially as shown and described and particularly pointed out in the claim.

In the accompanying drawings, Figure 1 15 shows a water faucet with syringe or syringe hose attached thereto and my new and original medicating device coupled up in the hose as in use. Fig. 2 is an enlarged view 20 of the hose and the valve coupling and the medicating device in longitudinal section therein, the said device being separated at its head.

As thus shown F denotes a faucet, H a 25 syringe hose attached thereto, C a valve coupling in the hose and D a medicating chamber in the hose and carrying the nozzle or other attachment N on its outer end.

Essentially the invention resides first in 30 the hose as a whole, and, secondly, in the said combined sponge and medicating chamber, which is regarded as both novel in itself and in its connection with the other parts shown. As a device simply and alone the said chamber comprises a cylindrical 35 body 2 having an externally threaded nipple 3 centrally at one end upon which the nozzle N, or other interchangeable instrument, is detachably engaged. At its other or opposite end said body or cylinder has a cap 40 4 threaded inside in this instance and adapted to screw onto the neck 5 of said body, and provided with an internally threaded hole 6 adapted to receive a threaded nipple 7 on the nose H. Now, as an important feature of construction of body 2, it is to be observed that in addition to the neck 5 at one 45 end it has an annular shoulder or enlargement 7 inside at said end and what may be regarded as the inner base of said neck and 50 which affords an offset and stop to confine the sponge S, or its equivalent, in said body or chamber. This leaves the inside of neck 5 and a portion of said cap unoccupied and wherein room is purposely provided for the

medicating tablet or wafer 8, such tablet or 55 wafer being introduced by removing cap or cover 4 and being itself of whatever character or contents a given treatment may require. The sponge serves as a medium for holding the tablet in its place as well as a 60 strainer through which the medicated water is carried. Relatively, therefore, the respective ends of body 2 of said chamber are 65 differently constructed, chamber 9 for tablet 8 necessarily being of a size to accommodate the tablet and provide flow of water about the same. Of course the sponge will 70 measurably modify the water pressure to the user regardless of other parts, but valve 10 in coupling C is intended for this purpose. 70

Obviously it would not be safe to the user of the syringe to permit the full volume and pressure of a normal city supply to be taken into the person without restraint, and as this 75 style of syringe hose is engaged directly with a faucet which almost invariably is removed beyond the reach of the user, he requires means to control the flow of the water more immediately in hand. Hence I have 80 incorporated valve 10 with the hose and in such nearness to the using end thereof that the same can be easily reached and manipulated by the hand of the user to regulate the volume and force of the flow. This also 85 serves to modify the absorption of the medicated wafer or tablet and affords a syringe and which entirely dispenses with the water bag heretofore depended upon for a head 90 and supply of water. In some cases it is desirable to use a liquid medicament or solution, in which case the sponge S may be saturated therewith, so that the sponge becomes a vehicle or medium for distribution 95 and filtration in this case also.

What I claim is:

As a new article of manufacture, a convertible attachment for syringe hose adapted to receive a medicament and consisting of a 100 hollow cylindrical body providing a chamber for the medicament and having an externally threaded nipple 3 at one end and a neck 5 at the other end externally threaded, a cap 4 screwed onto said neck and provided with a central threaded hole 6, a nipple 7 constructed at its outer end to engage hose thereon and externally threaded at its inner 105

end and screwed into said hole 6, the threaded end of said nipple *h* and the threaded end of nipple 3 being of the same size, whereby the device is rendered convertible and an instrument can be screwed directly onto nipple *h* and the said medicating body omitted or onto nipple 3 with said body in use.

In testimony whereof I affix my signature in presence of two witnesses.

CHARLES F. ACKERMAN.
